[57] ABSTRACT

The positioning of a treating fluid, such as an acidifying and/or particle-carrying fluid, in a subterranean location is improved by injecting a viscous, aqueous solution that contains a cellulose ether, a fluoride salt, a weak acid and a weak acid salt, and subsequently becomes a substantially non-viscous weakly acidic liquid that is capable of dissolving clay.

BUFFER-REGULATED TREATING FLUID POSITIONING PROCESS

RELATED PATENT APPLICATIONS

The present invention is related to, but is distinct from, the buffer-regulated mud acid solutions of the type described in the E. A. Richardson patent application, Ser. No. 444,207 filed 2/21/74. The present invention utilizes reactants similar to those that form the buffer-regulated mud acid solutions in combination with a viscosifier with which they react to provide a selected strength and duration of the viscosity of the solution. The pertinent disclosures of the prior application are incorporated herein by cross-reference.

BACKGROUND OF THE INVENTION

The present invention relates to a process, such as a well-treating process, in which a viscous fluid is pumped into a selected remote location, such as a subterranean location in or around the borehole of a well or a fracture. The invention is particularly useful for emplacing a slurry of particles that form a sand or gravel pack in or around a perforated casing in a well borehole, and/or within a fracture in a subterranean earth formation; for displacing a low-fluid-loss viscous, slow-reacting, acidic solution into and along the walls of a fracture; for temporarily diverting a relatively fast acting acid away from the more permeable zones that tend to act as "thief-zones" in an inhomogeneous permeable interval of earth formations in order to improve the permeability profile of the interval; and the like.

SUMMARY OF THE INVENTION

The invention relates to a process for injecting fluid into a selected remote location such as a location in or around the borehole of a well. At least one each of a cellulose ether, a fluoride salt, a weak acid and a weak acid salt are dissolved in an aqueous liquid. The compositions and proportions of the dissolved materials are arranged to provide a weakly acidic solution that is capable of dissolving clay and has a selected relatively high viscosity that breaks in response to a time-and-temperature exposure of selected severity. The temporarily viscous solution, or a combination of it with relatively inert components that provide a treating fluid having substantially the same acidity and viscosity properties, is pumped into the selected subterranean location before its viscosity is significantly reduced.

DESCRIPTION OF THE DRAWING

FIGS. 1 and 2 are schematic illustrations of portions of a well and reservoir formation in which the invention is being practiced.

FIGS. 3 and 4 illustrate plots of variations of viscosity with time of temporarily viscous solutions of various compositions.

DESCRIPTION OF THE INVENTION

In various situations, for example, where the treatment to be effected is primarily a delayed acidization, the injected fluid can comprise a temporarily viscous aqueous solution of the present type, with little or no additional material. Where relatively inert materials are combined with those solutions, the materials that are combined can comprise substantially any that can be dissolved in, emulsified with, or suspended in such a solution to form a fluid having at least one liquid

phase that is a weakly acidic, aqueous solution that is capable of dissolving clay (and/or silica) and has a viscosity that is, temporarily, relatively high. Examples of inert materials suitable for use in the invention include solid particles such as sand, gravel, walnut shells, or the like for forming sand or gravel packs in well boreholes or masses of popping agents within fractures in subterranean earth formations, corrosion-inhibiting materials, wetting-agents, fluid loss preventative materials, chelating agents, etc., such as those used in conventional types of acidizing, fracturing, gravel packing, or the like, operations. Where the inert materials are soluble in a weakly acidic aqueous liquid, they can be combined with the temporarily viscous aqueous solution, or its components, during or after the compounding of the solution. Where the inert materials are to be emulsified with or suspended in such solutions, such materials are preferably combined with the solutions after all of the solutes have been dissolved.

The present invention is, at least in part, based on a discovery that, relative to uses in well-treating operations and the time-temperature exposures to which fluids are subjected during such operations: (a) a mixture of at least one each of a fluoride salt, a weak acid and a weak acid salt, is capable of breaking the viscosity of a cellulose ether-thickened aqueous solution, (b) a cellulose ether-thickened aqueous solution containing a mixture of at least one each of a fluoride salt, a weak acid and a weak acid salt, is capable of becoming (before or after the viscosity of the solution has been reduced) a solution that has a relatively high pH but is capable of dissolving siliceous material and/or weak acid-sensitive material, and (c) the breaking time of the viscosity of a cellulose ether-thickened aqueous solution is sensitive to the pH of the solution (which is preferably within the range of from about 2 to 4) in a manner such that, at the temperatures usually encountered in well-treating operations, (within the range of from about 80° to 250°F), suitable viscosity-breaking times can be obtained by pH's of a mixture of at least one each of a fluoride salt, a weak acid, and a weak acid salt that provides a clay-dissolving weakly acidic solution.

Because of the above interrelation of properties, a slug of the present temporarily viscous, weakly acidic mud acid solution can be pumped into a depth interval containing permeable earth formations of different effective permeabilities, so that its viscosity tends to direct it into the most permeable portions, to there (a) dissolve fine particles of and thus to prevent permeability-impairment due to particle-movement, (b) divert portions of a more strongly acidic and faster-acting liquid to less permeable portions of the interval, and (c) subsequently become a relatively non-viscous liquid that can readily be removed from the interval. Alternatively such a temporarily viscous solution can be used as the carrying liquid for a slurry of sand or gravel or fracture-propping materials that is pumped into a borehole or a fracture to provide a self-cleaning mass of the particles. In the latter procedure, substantially all of the particles and all portions of the mass of particles are immersed in a liquid that (1) dissolves the clay or other acid-soluble fine particles (such as fines that were formed or entrained during the transporting of the slurry into the selected location), (2) maintains a pH that is relatively non-corrosive and (3) converts itself to a relatively non-viscous liquid that can readily be removed from the so-cleaned mass of particles.

Aqueous liquids suitable for use in the present invention include pure water or substantially any relatively dilute aqueous liquid that is compatible with dissolved fluoride salts, weak acids, weak acid salts and the acidification reaction products of hydrogen fluoride and clays or other siliceous materials. The aqueous liquid can advantageously contain additives such as corrosion inhibitors, wetting agent, detergents, oil solvents, oil and water mutual solvents, that are similarly compatible. Particularly suitable aqueous liquids include water or relatively dilute and soft saline solutions.

Fluoride salts suitable for use in the present invention include substantially any relatively water-soluble fluoride salt. The ammonium salts of hydrofluoric acid, such as ammonium fluoride and ammonium bifluoride, are particularly suitable. Where ammonium bifluoride is used, it is preferably mixed with enough ammonia or ammonia hydroxide to provide substantially equivalent proportions of ammonium and fluoride ions.

Weak acids that are suitable for use in the present invention include substantially any that dissolve in water to form an acidic solution adapted to convert fluoride ions to hydrogen fluoride. Examples of suitable weak acids include the water soluble fatty acids such as formic acid, acetic acid, and the like; substituted organic acids that are both relatively weak and water-soluble, such as chloroacetic acid, hydroxyacetic acid, and the like; various water-soluble polycarboxylic acids such as citric acid and the like. The weak acids can be used as individual acids or as mixtures of acids. Particularly suitable acids are formic, acetic and citric acids.

Weak acid salts suitable for use in the invention include substantially any water soluble salt of any weak acid of the type described above. Examples of suitable weak acid salts include the ammonium or alkali metal salts of the above acids, such as sodium or ammonium formate, sodium or ammonium acetate, sodium or ammonium citrate, or the like. The weak acid salts can be used as individual salts or as mixtures of salts. The salt of a given weak acid can be used with that acid or with one or more different weak acids. The latter arrangement can be utilized to provide a temporary adjustment in pH. For example, a relatively small proportion of a weak acid having a relatively high ionization constant (such as formic acid) can be mixed with a salt of a less ionized acid (such as ammonium acetate) to provide a solution having a pH that initially stays at a lower value than that exhibited after the depletion of the relatively highly ionized weak acid. Particularly suitable salts of weak acids include the ammonium salts of formic, acetic, and citric acids.

Where it is desirable to provide a temporarily viscous solution that is initially a relatively strongly acidic solution, a portion of a strong acid can be dissolved in the solution. While the strong acid is present, it over-rides the buffering action and depresses the pH of the solution. When the strong acid has been depleted, the pH rises to the value established by the buffering action corresponding to the relative proportions of weak acid and weak acid salt.

In the present temporarily-viscous solutions, the pH is strongly affected by the ionization constants and relative proportions of the weak acids and weak acid salts. In addition, where the fluoride salt concentrations are equivalent to less than about 5% by weight of aqueous hydrofluoric acid (about 2.5 moles per liter of the aqueous liquid), the hydrofluoric acid acts as a weak

acid, and the fluoride salt acts as a weak acid salt. In a solution containing a mixture of fluoride salt, weak acid, and weak acid salt, both the acidity of the solution and the rate of its dissolving of clay or weak acid-soluble material, decreases with increases in the pH of the solution. In addition, in a solution that contains a viscosifying amount of a cellulose ether, the rate at which the ether is hydrolyzed (which hydrolysis reduces the viscosity of the solution) is also decreased with increases in the pH of the solution.

In formulating the temporarily viscous solutions of the present invention, the composition and proportions of the cellulosic ether, fluoride salt, weak acid, and weak acid salt, are preferably correlated or arranged to provide both an adequate duration of the viscosity and an adequate capability of dissolving clay or acid-sensitive material. The clay-dissolving capability is increased by increasing the concentration of the fluoride salt (preferably to concentrations within a range equivalent to from about 0.1 to 3 moles per liter of hydrogen fluoride). The duration of the relatively high viscosity is increased (while decreasing the rate at which the solution dissolves clay or acid-sensitive material) by increasing the buffer-regulated pH of the solution (preferably to a pH within a range of from about 3 to 6). Where it is desirable to have a relatively high concentration of fluoride salt and still have a temporarily high viscosity of relatively short duration (along with a relatively rapid rate of acidification) the viscosity-breaking and initial acidification reaction rate can be increased by (a) adding a strong acid, such as hydrochloric acid, to the solution (preferably using less than an equal molecular proportion relative to the amount of weak acid) in order to temporarily override the buffer regulation of the pH, (b) using a weak acid having a relatively high ionization constant or (c), increasing the temperature of the subterranean location to be treated (as well as the conduit from that location to a surface location), for example, by inflowing a hot fluid.

Where the process of this invention is used for emplacing a self-cleaning mass or pack of particles in a selected location, the particles are preferably solid materials that are relatively slowly reactive with a "mud acid" (A HF-containing clay or silica-dissolving acid). Suitable particles include sand or gravel-sized, relatively spherical or well-rounded particles of silica sand grains, walnut shells, glass beads, mud-acid-resistant polymers, or the like. Where such particles are suspended in a temporarily viscous solution of this invention, the particles become emplaced in a mass in which all portions are permeated with a weakly acidic solution that is capable of dissolving clay or acid-sensitive fine particles. This tends to free the mass of any fine particles (such as fine sand, silt-sized, clay-sized, or smaller) of siliceous or acid-sensitive materials that are formed in or became mixed with, the pack particles. Such fine particles are commonly formed or entrained by the crushing and scraping action of the particles of a slurry that is flowed through pumps and/or conduits or along the face of earth formations, such as the walls of the borehole, or a fracture. The reactivities of the fine particles are many times greater than those of particles of from about 10 to 100 US mesh sieve sizes that are the preferred sizes for use in sand or gravel packing operations. When the packing particles and/or fracture-propping particles are suspended in the present temporarily viscous solutions and pumped into place,

the fines tend to be substantially completely dissolved with no significant loss of the packing particles, or other deleterious effect on the mass of packing particles.

Cellulose ether water thickeners that are suitable for use in this invention, include substantially any acid-sensitive cellulose ethers such as hydroxyalkyl, carboxyalkyl, or lower alkyl, cellulose ethers that are substantially completely water-soluble and are adapted to form water-soluble hydrolysis products when they are hydrolyzed in an acidic aqueous liquid. Examples of such cellulose ethers include hydroxyethylcellulose, carboxymethylcellulose, and the like. The hydroxyethylcelluloses available from Hercules Pattern Company, as "Natrosol," those available from Dowell as J-164, or from Halliburton as WG-8, are particularly suitable.

The present invention provides an improved process for acidizing a fracture in a subterranean earth formation while the fracture is being formed, extended, and/or packed with a propping agent. Fractures are formed by injecting fluid into a well at a pressure above the breakdown pressure of the surrounding earth formation. To keep the fracture open, a slurry of granular solids is injected to emplace a porous mass of particles between the walls of the fracture. While the fracture is being extended, the volume of the opening between its walls is determined by the injection rate and volume of the fracturing fluid, and the rate of fluid loss into the fracture walls. A relatively large volume of fluid free of fracture propping particles (although it may contain fine particles of a fluid-loss material) is usually injected ahead of the slurry of propping particles. The temporarily high viscosity of the present well treatment fluids adapts them to be pumped through the fractures without rapidly leaking-off into the walls of the fractures. Their capability of reacting slowly, but relatively extensively, with clays or other siliceous materials, adapts them to continue to dissolve such materials, and thus increasing the matrix permeability of the earth formations forming the walls of the fracture. In this connection, it is advantageous to use relatively high concentrations of fluoride salt to form relatively high pH temporarily viscous solutions that react slowly with respect to both the reduction of their viscosity, and the dissolving of clay, since such solutions can be allowed to remain in the fracture walls for relatively extensive times, such as one or more days.

As known to those skilled in the art, the severity of the time-temperature exposure of reactive materials, such as the present temporarily viscous aqueous solutions are increased by increases in either the degree of the temperature exposure for a given time, or the duration of the exposure at a given temperature. In a well treating operation, it is not usually feasible to make significant changes in the temperature of the subterranean location to be treated (or the conduit extending from it to a surface location) although some change can sometimes be made injecting a relatively hot or cold fluid. In addition, except in a fracturing operation, the rate at which fluid is pumped from a surface location to the subterranean location, is generally limited by the rate at which fluid can be flowed into the pores of the earth formation in response to a pressure less than the fracturing pressure. In formulating the present temporarily viscous solutions, the composition and proportions of the solution component are preferably arranged to provide a viscosity reduction in response to

a time-temperature exposure that can feasibly be attained in pumping that solution into the particular subterranean location to be treated.

FIG. 1 illustrates a particularly suitable process for using the present invention in gravel packing a well. It shows a borehole 1 extended into a subterranean reservoir 2. The borehole contains a string of casing 3, surrounded by a sheath of cement 4 and penetrated by perforations 6, which provide openings into the reservoir. The invention also can be used in uncased boreholes or boreholes in which a casing is surrounded by a grouting material other than cement. A tubing string 7 which is connected to a screen or perforated liner 8 (along with appropriate packing, hanging, crossover devices, and the like, for a gravel-packing operation) has been inserted within the casing.

As indicated by the arrows, fluid is pumped through the tubing string and into the reservoir. The fluid preferably comprises a series of individual portions or slugs.

20 The fluids shown in the Figure are preferably preceded by fresh water and/or an aqueous solution of an ammonium salt (such as ammonium chloride) and/or an acid adapted to dissolve carbonates or other reactive alkaline earth metal salts, where desirable to dissolve carbonate minerals and/or to displace reservoir water that contains a significant proportion of dissolved salts of alkali metals or alkaline earth metals. Slug 9 is a pre-formed mud acid. It can advantageously be a self-neutralizing solution of hydrochloric and hydrofluoric acids and a pH-increasing reactant of the type described in the co-pending patent application of E. A. Richardson and R. F. Scheuerman, Ser. No. 274,778, filed July 24, 1972 (the disclosures of which are incorporated herein by cross-reference). Slug 10 is a spacer slug, such as a relatively dilute aqueous solution (of not more than about 5% by weight) of ammonium chloride. Slug 11 is a buffer-regulated mud acid solution, comprising an aqueous solution of a fluoride salt, a weak acid and a weak acid salt in proportions that form a significant but low concentration of hydrogen fluoride, of the type described in the above-identified patent application Ser. No. 444,207. Slug 12 is a temporarily viscous solution of the present invention that contains a small proportion (such as about 3% by weight) of ammonium chloride, but is free of gravel-packing particles. Slug 12 functions as both a fines-removing mud acid and a viscous fluid that precedes the gravel pack particle-containing slurry for inhibiting the settling of pack particles while the pack particle-containing slurry and the fluid ahead of it are traveling through the conduits in the well.

55 Fluid 13a is a filtrate from slug 13. Slug 13 is a slurry of gravel-packing particles suspended in a temporarily viscous solution of the present invention. The filtrate 13a flows on into the reservoir as a temporarily viscous solution as the suspended packed grains are screened out against the face of the reservoir. Fluid 13b is a supernatant liquid comprising a temporarily viscous solution of the present invention, from which the gravel-packing grains have settled out (by gravity segregation) as portions of the slug 13 stands still or flows relatively slowly within the borehole.

60 Fluid 14 is an inert gravel packing slurry-displacing fluid, such as a relatively dilute aqueous solution of an ammonium halide. Fluid 14 can advantageously contain a pH-increasing reactant such as a readily hydrolyzable amide. The volume and extent of displacement

of the slugs 13 and 14 are preferably controlled so that (a) slug 13 fills the annular space around the screen 8 and extends above the uppermost perforation 6 in the casing 3 and (b) slug 14 fills the portion of the casing above that space, up through the crossover assembly, and into the tubing string 7.

FIG. 2 shows the same portion of the same well at a later time, when fluid is being produced into the well from the reservoir 2. At this time the well contains a gravel pack 16, which has been formed by the screening out and settling of the gravel pack particles that were transported by slurry 13.

As shown by the arrows, the produced fluid tends to flow directly from the perforations 6, through the gravel pack 16, and into the adjacent openings in the screen or liner 8. Thus, the produced fluid contacts only a small portion of the gravel pack and is confined within an inner conduit during most of its passage out of the well. Because of this, the production of fluid from the reservoir tends to leave a substantially undisturbed column of the fluids 13b and/or 14 standing within and/or above the gravel pack 16. Since the fluid 14 is apt to be mixed with the substantially non-viscous but relatively weakly acidic liquid that is formed by the self-induced conversion of the supernatant temporarily viscous fluid 13b (shown in FIG. 1), the fluid 14 can advantageously contain a pH-increasing reactant for reducing the corrosiveness of an acidic liquid.

The flow patterns of fluids that are injected or produced through a well containing a gravel pack, are such that the self-cleaning aspect of the present process is particularly advantageous. In the present process the particle-suspending fluid (which is initially viscous and is distributed throughout the entirety of the gravel pack) comprises a weakly acidic and relatively slowly-reactive mud acid that tends to dissolve substantially all of any silt-sized or clay-sized fine particles of siliceous material or acid-soluble material that becomes entrained within the pack or along any of its peripheral areas. The perforations 6, or other open portions of borehole wall (e.g., the walls of an open hole or "bare-foot" completion) through which fluids can flow between the interior of the well and the interior of the reservoir are, in effect, parallel flow paths. If one such path is plugged, most of all of the flow proceeds through another path. Because of this, it is seldom effective to inject a mud acid into a gravel pack (such as pack 16) after it has been emplaced. Such an injection usually fails to dissolve fines throughout any but small and preferentially permeable portions of the body of the pack or along the interfaces between the pack and/or pack or perforations or perforation tunnels and the face of the reservoir.

In preparing a temporarily viscous solution of the present invention for use in a well, a volume of approximately 1,000 gallons is preferably mixed as follows; about 884 gallons of fresh water are mixed with about 80 pounds of a water-soluble hydroxyethylcellulose, 308 pounds of ammonium fluoride, and 250 pounds of ammonium chloride. Before pumping the solution into the well, about 85.6 gallons of aqueous 90% formic acid, and 29.75 gallons of aqueous 30% hydrochloric acid are added. This forms a temporarily viscous solution having a viscosity (in centipoises, about 350 at 80°F and about 100 at 170°F) that is significantly reduced by a time-temperature exposure equivalent to about 4 hours at 170°F.

FIG. 3 shows the results of laboratory tests of the effect of pH on the viscosity-breaking times of aqueous solutions thickened with a hydroxyethylcellulose ether.

Stock aqueous solutions were prepared by dissolving in potable water about 80 pounds per 1,000 gallons of a commercially available hydroxyethylcellulose, 0.1 pound per barrel of water of sodium hydroxide, and 3% by weight (based on the water content) of ammonium chloride. The following reactants were then dissolved in the stock solution in proportions providing substantially the indicated pH's and number of moles per liter (based on the water content) of the following acidifying materials:

- 15 Solution A — 2 moles formic acid, pH 1.5
- Solution B — 1 mole formic acid, pH 1.8
- Solution C — 1 mole acetic acid, pH 2.4
- Solution D — 0.75 mole formic acid, 0.25 mole sodium formate, pH 3.0
- 20 Solution E — 1 mole formic acid, 1 mole sodium formate, pH 3.4
- Solution F — 0.5 mole formic acids, 0.5 mole sodium formate, pH 3.6
- Solution G — 1 mole acetic acid, 1 mole sodium acetate, pH 4.7

25 FIG. 3 shows the variations in the viscosities of the respective solutions (in terms of transit times in seconds through a No. 300 Ostwalt tube, in which a fluid having a viscosity of about 1 centipoise has a transit time of about 2.5 seconds) versus the time (in hours) at which the solutions were kept at a temperature of 180°F. It is apparent that the extents of time-temperature exposure that causes a significant reduction in the viscosity of the tested solution (such as a reduction to about 10 centipoises, which corresponds to a transit time of about 25 seconds) increase with increases in the pH of the solutions. It is also apparent that a buffered system comprising a mixture of a weak acid and a weak acid salt can be used to adjust the pH of such a solution.

30 40 FIG. 4 shows the results of similar tests of similar solutions containing the same proportion of hydroxyethylcellulose. These solutions each contained about two moles per liter of formic acid and 1 mole per liter of ammonium fluoride and were maintained at 170°F. The solutions differed from each other as follows:

- Solution A — contained 0.5 mole per liter hydrochloric acid, pH 3.0
- Solution B — contained 0.25 mole per liter hydrochloric acid, pH 3.3
- 50 Solution C — contained no hydrochloric acid, pH 4.0

55 Test results, such as those shown in FIGS. 3 and 4, indicate the fluoride salt functions as a weak acid salt component of the buffer system that regulates the pH of the solution. For example, the 2m formic acid solution A of FIG. 3 has a pH of 1.5 while solution C of FIG. 4, which differs significantly only in an addition of 1 mole per liter of ammonium fluoride, has a pH of 4.0. Such tests also indicate that relatively small proportions of a strong acid, such as hydrochloric acid, can be added to obtain a lower pH. The lower pH provides a quicker breaking of the viscosity, as well as a faster rate of dissolving a siliceous material or a weak acid-soluble material. The more rapid acidizing effect of a relatively low pH is more completely described in the above-identified patent application Ser. No. 444,207.

60 65 What is claimed is:

1. A well treating process comprising

dissolving in an aqueous liquid at least one each of a cellulose ether, a fluoride salt, a weak acid, and a weak acid salt;

arranging the composition and relative amounts of the solution components to provide a temporarily viscous solution that is weakly acidic but is capable of dissolving clay and has a selected relatively high viscosity that is significantly reduced in response to a time-temperature exposure of selected severity; and

flowing the temporarily viscous fluid into a subterranean location at a rate such that it at least substantially reaches the location to be treated before its viscosity has been significantly reduced.

2. The process of claim 1 in which at least a portion of the temporarily viscous solution is combined with relatively inert material, to form a treating solution having substantially the same acidity and viscosity properties, prior to flowing it into the subterranean location.

3. The process of claim 2 in which the relatively inert material includes solid particles adapted to form a sand or gravel pack or a fracture-propping mass of particles.

4. The process of claim 1 in which a relatively small proportion of strong acid is mixed with the temporarily viscous solution to increase its initial rate of reaction and reduce the duration of its relatively high viscosity.

5. The process of claim 1 in which the temporarily viscous solution is arranged to have a pH of from about 2 to 4.

6. The process of claim 1 in which the temporarily viscous solution is flowed into a fracture within a subterranean earth formation and, before flowing it into the fracture, the composition and proportions of its components are arranged to provide a relatively high pH.

7. The process of claim 6 in which slugs of the temporarily viscous solution are alternated with slugs of a relatively fast-acting acidic material.

8. A well treating process comprising

dissolving in an aqueous liquid at least one each of a cellulose ether, a fluoride salt, a weak acid, and a weak acid salt;

arranging the compositions and proportions of said solutes to provide a temporarily viscous solution that is weakly acidic but is capable of dissolving clay and has a viscosity that is significantly reduced in response to a time-temperature exposure of selected severity;

combining the temporarily viscous solution with relatively inert material to the extent desired to provide an earth forming treating fluid having properties of acidity and viscosity substantially equaling those of the solution; and

flowing the earth formation treating fluid into a subterranean location to be treated before the solution viscosity is significantly reduced.

9. The process of claim 8 in which the earth formation treating fluid contains suspended solid particles adapted to form a permeable mass of particles in the subterranean location to be treated.

10. The process of claim 8 in which a relatively small proportion of a strong acid is mixed with the temporarily viscous solution to increase its initial rate of acidization reaction and reduce the duration of its relatively high viscosity.

11. The process of claim 8 in which the compositions and proportion of the components of the the temporarily viscous solution are arranged to provide a relatively high pH and the earth formation treating fluid containing that solution is flowed into a fracture within a subterranean earth formation.

12. In a well treating process in which a self-breaking viscous fluid having a selected initial viscosity is injected into a selected subterranean location in response to a selected injection pressure, an improved process for ensuring that the viscosity-breaking occurs at a selected time after the solution has reached the selected location, which process comprises:

determining the magnitude of the time-temperature exposure of fluid that flows from a surface location to the selected subterranean location at the rate established by the selected injection pressure;

determining the pH at which an aqueous solution that contains enough cellulose ether to provide the selected viscosity mixed with an acid capable of inducing the breaking of the viscosity becomes a solution in which the viscosity-breaking occurs at the selected time after the solution has been subjected to a time-temperature exposure of the determined magnitude and is maintained at the temperature of the selected subterranean location; and

injecting as said self-breaking viscous fluid a cellulose ether-thickened aqueous solution having a pH substantially equaling the determined pH.

13. The process of claim 12 in which the pH of said injected fluid is established by a dissolved mixture of at least one weak acid and one weak acid salt in a ratio that buffers the pH at substantially the determined pH.

14. The process of claim 12 in which said injected fluid contains at least one dissolved salt of hydrofluoric acid.

15. The process of claim 14 in which said injected fluid has a pH of from about 2 to 4.

16. In a process in which the fluid is positioned in a selected remote location by forming a temporarily viscous fluid and flowing it into the selected location before the fluid viscosity is significantly reduced, the improvement which comprises:

dissolving in an aqueous liquid at least one each of a cellulose ether, a weak acid and a weak acid salt;

arranging the solution components to provide a weakly acidic solution having a viscosity that becomes significantly reduced in response to a time-temperature exposure of selected severity; and

flowing the weakly acidic solution into the selected location at a rate causing it to arrive at least substantially as soon as it has received a time-temperature exposure of the selected severity.

17. The process of claim 16 in which the selected location is a subterranean region in contact with earth formation in or around the borehole of a well.

18. The process of claim 16 in which the weak acid salt comprises a mixture of at least one salt of hydrofluoric acid and at least one salt of an organic acid.

19. The process of claim 18 in which the weakly acidic solution contains an amount of strong acid that is significant but less than equimolar relative to the amount of weak acid.

20. The process of claim 18 in which the strong acid is hydrochloric acid.

21. The process of claim 20 in which the pH of the buffer regulated solution is, initially, from about 2 to 4.
